UNITED STATES PATENT OFFICE.

JOAKIM JAKOBSEN, OF VIKELAND, NEAR KRISTIANSSAND, NORWAY.

CALENDAR.

Application filed October 24, 1924. Serial No. 745,681.

To all whom it may concern:

Be it known that I, JOAKIM JAKOBSEN, a subject of the King of Norway, and residing at Hunsfos, Vikeland, near Kristianssand, Norway, have invented certain new and useful Improvements in a Calendar; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has for its object a perpetual calendar which is adapted for adjustment so as to be used for any number of consecutive years.

According to the present invention the calendar comprises a single band or ribbon which is provided in two parallel rows with the dates from the 1st of January to 31st of December as well as the days of the week repeated continuously.

This band or ribbon which is preferably mounted on two parallel rollers is covered on the front side with a disc or screen, provided with one or more openings for the date and one opening corresponding to a number of consecutive days of the week.

According to one form of the invention the screen is provided with one opening for the date and another opening covering all the seven days of the week, the latter opening being adapted to be closed by slides so as to show only the week day corresponding to the date appearing in the date opening.

According to another form of the invention two date openings are provided, either of which may be opened or covered, and which co-operate with another opening sufficiently large to show four consecutive days of the week.

By covering one of the date openings and three-fourths of the other openings a predetermined date may be adjusted to appear simultaneously with any day of the week.

On the drawings:

Fig. 1 is a transverse section through one form of the calendar, and

Fig. 2 a front view of the covering screen with its openings.

Fig. 3 is a diagrammatic view of the cov-

ering screen with openings according to a modified form of the invention.

As will be seen from Fig. 1 the calendar comprises a single band or ribbon 2, mounted on two rollers 3 and 4, one or both of which may be provided with handles for winding the band 2 from one roller to the other. 60 Numeral 10 indicates the fastening device for the ends of the band. On the front side the calendar housing is covered by a covering disc or screen 5, having one opening 6 through which one of the dates printed in a continuous row on the band 2 may be shown, and another opening 7 sufficiently long to show all the seven days of a week, the days of the week being repeated continuously in a second row on the same band 2. The opening 7 is provided on both sides with guides 8 for a number of covering slides 9. These slides 9 may be adjusted or shifted so as to leave any predetermined part of the opening 7 free, thus making any particular day of the week visible. The slides 9 fit snugly into the guides 8 and are frictionally retained in place. On the 1st of January of each year the band is adjusted, so as to make the date 1st of January visible through opening 6, 80 and slides 9 are placed so as to make visible the day of the week corresponding to the 1st of January of the particular year.

Instead of using separate slides 9 for covering the parts of the ribbon otherwise visible through opening 7, any other suitable means having similar functions may be utilized.

According to the form diagrammatically illustrated by Fig. 3 the days of the week opening 7 is only large enough to make visible four consecutive days of the week, and two openings 6^a and 6^b are provided for showing the dates. The distance between the two date openings 6^a, 6^b is equal to the distance between three days as printed on the band 2, and either of the openings 6^a, 6^b may be used.

If the upper opening 6^a is used, it will be noted that the date 1st of January may be 100 shown together with any of the four last days in the week, whereas if the lower opening is used, the 1st of January may be shown together with any of the four first days of the week or vice versa, depending on the 105 placing of the respective columns of days of

the week, and dates, on the band 2. Thus by choosing the correct date opening, the 1st of January and accordingly the following dates of the year may be made visible together with any day of the week desired.

What is claimed is:

1. In a perpetual calendar the combination with a rotatable band provided with the consecutive dates of a year arranged in one row and the days of the week continuously repeated in another row parallel to the first, of a screen for covering said band, said screen being provided with an opening for rendering visible a date provided on the band, and said screen having another opening sufficiently large to render visible a plurality of consecutive days of the week on the band, and means for obturating part of the second opening, so as to make only one day of the week visible through the same.
2. In a perpetual calendar, a band, two parallel rotatable rollers, on which the band is mounted, a screen covering part of the band between the said two rollers, said band being provided with two parallel rows of consecutive dates of the year and continuously repeated days of the week respectively, said screen being provided with a plurality of openings for rendering visible a date on

the band, and said screen having another 30 opening sufficiently large to make visible at least four consecutive days of the week, and means for obturating one of said date openings and part of the large opening, so as to make only one day of the week visible 35 through the same.

3. In a perpetual calendar a band, two parallel rotatable rollers on which said band is mounted, a screen covering part of the band between the said two rollers, said band 40 being provided with two parallel rows of consecutive dates of the year and continuously repeated days of the week respectively, said screen being provided with an opening for rendering visible a date on the band, and said screen having another opening sufficiently large to render visible a plurality of consecutive days of a week on the band, said last opening being provided with shiftable means to close part of the opening, so as to 45 make only one day of the week visible.

In testimony that I claim the foregoing as my invention, I have signed my name in presence of two subscribing witnesses:

JOAKIM JAKOBSEN.
